UNITED STATES PATENT OFFICE

148,929

DESIGN FOR A PICTURE FRAME

Paul L. Hartnett, Leominster, Mass.

Application October 5, 1946, Serial No. 133,776

Term of patent 7 years

(Cl. D29—20)

To all whom it may concern:

Be it known that Paul L. Hartnett, a citizen of the United States, residing at Leominster, in the county of Worcester and State of Massachusetts, have invented a new, original, and ornamental Design for Picture Frame, of which the following is a specification, reference being had to the accompanying drawing, forming part thereof.

Fig. 1 is a view in front elevation; Fig. 2 is a view in rear elevation; Fig. 3 is a top plan view; and Fig. 4 is a view in edge elevation, of a picture frame, showing my new design.

I claim:

The ornamental design for a picture frame, as shown.

PAUL L. HARTNETT.
